(57) **CLAIM**

The ornamental design for a footwear, as shown and described.

DESCRIPTION

FIG. 1 is front, top and right side perspective view of a footwear according to the new design;

FIG. 2 is a bottom and right side perspective view of the embodiment of FIG. 1;

FIG. 3 is a right side elevation view of the embodiment of FIG. 1;

FIG. 4 is a left side elevation view of the embodiment of FIG. 1;

FIG. 5 is a front elevation view of the embodiment of FIG. 1;

FIG. 6 is a back elevation view of the embodiment of FIG. 1;

FIG. 7 is a top plan view of the embodiment of FIG. 1; and, FIG. 8 is a bottom plan view of the embodiment of FIG. 1. The broken lines in the drawings show portions of the footwear that form no part of the claimed design.

1 Claim, 8 Drawing Sheets
